UNITED STATES PATENT OFFICE.

WILLIAM H. HEYBECK, OF PITTSBURG, PENNSYLVANIA, ASSIGNOR, BY DIRECT AND MESNE ASSIGNMENTS, OF TWO-THIRDS TO FRANK B. DAWSON, OF MCKEESPORT, PENNSYLVANIA, AND J. L. B. DAWSON, OF BEAVERFALLS, PENNSYLVANIA.

DRUMHEAD.

SPECIFICATION forming part of Letters Patent No. 729,936, dated June 2, 1903.

Application filed July 28, 1902. Serial No. 117,324. (No model.)

To all whom it may concern:

Be it known that I, WILLIAM H. HEYBECK, a citizen of the United States of America, residing at Pittsburg, in the county of Allegheny and State of Pennsylvania, have invented 5 certain new and useful Improvements in Drumheads, of which the following is a specification, reference being had therein to the accompanying drawings.

10 This invention relates to certain new and useful improvements in heads for drums and similar instruments; and the primary object thereof is to provide a drumhead which is produced by chemically treating fabric.

15 Broadly, the invention comprises one or more thicknesses of woven fabric—such as silk, satin, linen, &c.—which are gummed together and treated on their outer faces with a stiffening composition composed of shellac, 20 mercury, oxalic acid, and salt.

In describing the invention in detail reference is had to the accompanying drawings, forming a part of this specification, and wherein like numerals of reference indicate 25 like parts throughout the several views, in which—

Figure 1 is a fragmentary vertical section of a drum provided with heads constructed in accordance with the present invention. 30 Fig. 2 is a section of the snare-head, or modified form of my device. Fig. 3 is a similar view of the batter-head, or preferred form of the present invention. Figs. 4 and 5 are detail fragmentary views of the top and lower 35 layers of fabric constituting the batter-head and showing the arrangement of the weaving, and Fig. 6 is a similar view showing the two layers arranged in their relative positions.

40 In the drawings, 1 indicates the drum, 2 the snare-head, and 3 the batter-head thereof. 4 indicates the hoops for securing the respective heads in position, and 5 one of the hoop-clamps.

45 The drum, hoops, and clamp may be of any desired construction, inasmuch as they do not form any part of the present invention.

50 My invention, as heretofore stated, consists entirely in the construction of the respective drumheads, which, as will appear in the following description, are very similar.

In constructing the batter-head I employ two thicknesses or layers of fabric (indicated by the reference-numeral 6) and which are gummed on their inner faces, as at 7. 8 indicates layers of stiffening composition, which are placed on the outer faces of the respective thicknesses of fabric. As shown in Figs. 4, 5, and 6, the warp and weft threads of thickness of cloth are angularly disposed to the warp and weft threads of the two thicknesses of cloth and are arranged at an angle to each other, whereby the head is materially strengthened.

In the modified form of my device I employ but a single thickness of cloth 6^a, and therefore an adhesive material is not employed, but each face of the cloth is coated with a layer of stiffening composition 8^a in a manner to be hereinafter described. The composition with which I treat the outer faces of the fabric is composed of shellac, mercury, oxalic acid, and salt. These ingredients are first thoroughly mixed and then spread on the fabric and allowed to dry. After drying for a short period the drumhead is steamed, thereby drawing out the mercury and hardening the composition.

By the employment of a drumhead constructed in accordance with the present invention much softer and sharper tones are produced than can be obtained from the ordinary gut heads. Further, a much cheaper article is produced.

It will be obvious that various changes may be made in the details of construction without departing from the general spirit of my invention.

Having fully described my invention, what I claim as new, and desire to secure by Letters Patent, is—

A drumhead formed of fabric and having one of its faces treated with shellac, mercury, oxalic acid and salt.

In testimony whereof I affix my signature in the presence of two witnesses.

WILLIAM H. HEYBECK.
